CRUSHER FRAME

William A. Battey, Haverford Township, Delaware County, Pa., assignor to Pennsylvania Crusher Company, New York, N. Y., a corporation of New York

Application June 16, 1933, Serial No. 676,138

1 Claim. (Cl. 83—53)

My invention relates to the construction of crushing machinery employed for the purpose of reducing mineral bodies such as coal, ore, limestone, gypsum rock, and the like, and more particularly to an improved frame construction for crushers of the roll type.

Heretofore frames for crushers of the above-described type have been cast metal structures, usually made of a plurality of cast members held in properly assembled relation by dowels, bolts, and like fastenings. With a view of resisting the twisting or torsional stresses, caused by crushing strains, to which they are subject when in use, these crushing structures have been unnecessarily heavy and cumbersome. But weight alone does not insure the frame against breakage, and the principal object of my invention is to provide a frame of sufficient strength that will be much lighter than those heretofore made.

The feature of my invention is the provision of a one-piece frame, made up of a plurality of preformed parts welded together in proper relation and position. With such construction, not only is the weight of the frame materially reduced, but a frame is provided which is less likely to be damaged by reason of twisting stresses than the cast frames of roll crushers heretofore known.

A further object of my invention is to provide a relatively light frame of maximum strength, properly reinforced throughout its extent and particularly adapted for resisting stresses incident to the use of crusher structures of the roll type.

An embodiment of my invention is illustrated in the accompanying drawings, in which:

Figure 1 is a side elevation of a frame for single roll crushers, embodying features forming the subject of my invention.

Fig. 2 is a longitudinal sectional view of the structure shown in Fig. 1, taken on the line II—II, Fig. 3.

Fig. 3 is an end elevation looking in the direction of the arrow a, Figs. 1 and 2.

Fig. 4 is a cross sectional view on the line IV—IV, Fig. 1; certain of the parts of the crushing mechanism being diagrammatically illustrated, and

Fig. 5 is a fragmentary view, illustrating a modified construction of the side frames to facilitate mounting of the crusher roll and its shaft.

The crusher frame comprises a plurality of preformed metal sections, including side plates or members 10, 10, of channel formation, and cross members secured to and spacing said side members apart in proper position. The side members 10 are preferably made from plates of the desired size, suitably bent substantially at right angles to their broad surfaces to form top and bottom flanges 10^a and 10^b, respectively.

The flanges 10^b may be reinforced for bolt connections by welding short plate sections 10^c to the same. The side members 10, 10, are connected together and spaced apart by cross members disposed at their respective ends and indicated at 11, 12, and 13; such cross members being secured to the side members by welding, electrically or otherwise, as indicated at x.

The member 11 forms an end wall for the crushing chamber A, in which the roll B is mounted, and is provided with upper and lower flanges 11^a and 11^b, preferably arranged in planes opposite the flanges 10^a and 10^b of the side members 10, 10, and to which they are welded. This end wall member 11 may be curved in the manner indicated in Fig. 2, in order that the driving shaft may lie outside such end wall. The crusher frame is substantially open at top and bottom, and such frame, consisting of a plurality of preformed elements welded together, may be described as a topless and bottomless rectangular structure of unit formation.

Each of the side members 10, 10, may be provided with three circular openings, 14, 15, and 16, into which tubular sections 17, 18, and 19 are inserted and welded in place; such sections forming, respectively, dead-eye bearing housings for a drive shaft, a roll shaft, and a rod or shaft from which a breaker plate is hung. By preference, these bearing housing sections are solid members—sections of rolled shafting, for instance—which are bored, after they have been welded in place, for the reception of bushings in which the respective shafts are mounted.

The drive shaft bearing housings 17 and the roll shaft bearing housings 18 of the respective side members 10 may be interconnected at their peripheries by flange or rib elements 20 welded to each of said bearing housings and to said side members. Additionally, flange elements 20^a extend from the bearing housings 17 to the ends of the side members. Each of the bearing housings 17 and 18 is supported by a rib or flange element, indicated at 21 and 22, respectively, and these elements are welded in place against each side frame 10 and between the lower outer edge of each bearing housing and the lower flange 10^b of the channel members forming such side frames; the rib 21 abutting one of the bolt connection reinforcements 10^c. Reinforcing ribs or flanges 23 and 24, extending radially from the upper edge of the roll shaft bearing housing 18, are welded against the side frame 10 and to the upper flange 10^a of the same. Thus the bearing housings 17 and 18 are rigidly interconnected and supported at their outer ends by reinforcing ribs or flanges welded thereto and to said side members 10.

Secured to the lower right hand end plate or cross member, indicated at 12 (Fig. 2), is a tubular section 33 through which may pass a rod 60

or bolt, adapted to hold the breaker plate C in proper position and forming adjusting mechanism therefor. A bottom plate 12^a extends between the side members 10; being welded thereto 5 and to the lower edge of the cross member 12, and internally of this portion of the structure vertically disposed knee plates or partitions 12^b are welded to the end plate 12 and the bottom plate 12^a. Reinforcing flanges or ribs 35 welded 10 to the side members 10, 10, and to the roll shaft bearing housings 18 carried thereby, extend diagonally from the latter and pass around the end member 12 of the crusher frame and are welded to such end member and to said tubular section 15 33. By means of such flanges or ribs 35, the roll shaft bearing housings are rigidly connected to the lower end member 12 of the frame and to the section 33 through which the adjusting rod passes. Additionally, the ribs or flanges 35 20 may be supported intermediate their length by reinforcing ribs or flanges 35^a, which abut the bolt connection reinforces 10^c.

The end member 13 may be made of a plate bent to the cross-sectional form shown in Fig. 2, 25 with the flanged portions 13^a and 13^b; the lateral edges of said member 13 being welded to the inner wall surfaces of the side frame members 10. This arrangement provides a fixed heel (which may have a wear member as indicated by dotted 30 lines) for crushing, above the mounting for the breaker plate C; the latter being adjustable without constricting the opening of the crushing chamber and permitting the handling of large lumps when the structure is employed for coarse 35 crushing.

As is well known, the stresses imparted to the roll shaft vary continuously and as a result, the bearing housings carrying this shaft are subject to continuously changing stresses. Likewise, the 40 drive shaft is subject to continuously varying stresses due to variations in the quantity and/or character of the material being crushed. Consequently, it is necessary to provide means not only to suitably support the shafts but to eliminate 45 bending stresses which would otherwise cause fatigue and early breaking down of the frame. To this end, more reinforcing ribs or flanges than are necessary to support the bearing housings are provided. For instance, either of the ribs or 50 flanges 23 or 24 might be eliminated without materially affecting the support given to the bearing housings 18, but the elimination of either would undesirably increase or, more properly expressed perhaps, fail to decrease sufficiently the 55 amount of unsupported frame surface which, without such reinforcing ribs or flanges, would tend to weave or bend. In addition to the flanges or ribs 20, 23, 24, and 35, carried by the side frames 10, I may provide the ribs or flanges 25 60 and 26; the former connecting the bearing housings 18 and 19, and the latter lying between the bearing housing 19 and the upper flange 10^a of the side member 10.

The several flanges carried by and welded to 65 the side plates 10, among which may be mentioned those indicated at 20, 25, and 35, which intimately connect together, and to said plates 10, the drive-shaft bearing housing 17; the roll-shaft bearing housing 18; the breaker-plate supporting rod bearing housing 19, and the section 33 through which the breaker-plate adjusting rod passes, are of a weight and disposition sufficient 70 to take all of the stresses to which the structure

may be subjected; such arrangement producing a rigid frame wherein such side plates 10, largely functioning as walls defining the crushing chamber, are relieved of all stress.

While the end member 11 does not carry side 5 flanges, it is rendered rigid by the welding of its lateral edges to the inner surface of the side frame member 10, 10, taken in conjunction with its curved shape. By making the bend in this member in the manner indicated and sufficiently 10 deep, the drive shaft may be located outside of the crushing chamber and at the same time liberal space is preserved within the frame for reception of material undergoing crushing.

In the embodiment of my invention illustrated 15 in Fig. 5, I have shown a split bearing housing comprising the sections 50, 50^a, to serve as a support for the roll shaft; the lower part 50^a of which bearing housing is welded to the side plate 10, and to the ribs or flanges 20, 22, and 35. In 20 the development of a structure involving this construction, substantially wedge-shaped recesses or openings are cut in the side members 10, and ribs or flanges indicated at 51 and 51^a may be welded to the side members at the lateral edges 25 of these openings. In the space between these flanges 51 and 51^a, a plate segment 52, flanged at 52^a to overlie the flanges 10^a of the side members 10, may be fitted. This segment overlies the upper half 50 of the bearing housing and is provided with side flanges or ribs 53, 53^a abutting the flanges 51 and 51^a. It may be secured in place in any suitable manner; by bolts 54 and 55, for instance, or by a through bolt as indicated at 56, in lieu of the bolts 55. The upper bearing 30 housing section 50 may be secured to the ribs or flanges 20 and 35 by bolts 57.

Various departures may be made from the above-described and illustrated embodiments of my invention without departing from the spirit 40 and scope thereof as set forth in the appended claim.

I claim:

A unit frame for roll crushers comprising vertical side walls in parallel relation and each of 45 said walls having a plurality of openings of which some are larger than others; said openings being in transverse alignment, bearing housings mounted in said larger openings and welded to said walls; said walls consisting of integral rolled plate 50 members with outturned top and bottom flanges horizontally disposed, reinforcing ribs welded to the outer surface of said walls between the bearing housings and between the bearing housings and said flanges of the side walls for reinforcing 55 said side walls and supporting said bearing housings, a cross member of channel form transversely disposed between the vertical side walls at one end of the frame and extending from top to bottom of the same, a cross member at the opposite 60 end of the frame transversely disposed above one set of the bearing housings; said cross-members defining the longitudinal dimensions of the crushing chamber and being welded at their end edges to said side walls, a base plate disposed between said side walls at one end of the frame and having its end edges welded to said side walls, and a vertical end plate connected to said base plate and the side walls; one pair of said reinforcing ribs extending from the outer surface of 65 said vertical side walls around said end plate.

WILLIAM A. BATTEY.
